(Cl. D61—1)

FIG. 1

FIG. 2

FIG. 3.

FIG. 4.

FIG. 5

FIG. 6

FIG. 1 is a front elevational view of the rear projection film viewer for aircraft or similar vehicles, showing my new design in closed position;

FIG. 2 is a front elevational view in open viewing position;

FIG. 3 is a side elevational view;

FIG. 4 is an opposite side elevational view;

FIG. 5 is a bottom plan view; and

FIG. 6 is a rear elevational view thereof;

The drawing figures are stippled to indicate contrast in appearance. Portions of the figures are diagonally lined to indicate translucency.

I claim:

The ornamental design for a rear projection film viewer for aircraft or similar vehicles, as shown and described.
